UNITED STATES PATENT OFFICE.

JOHN F. SPRINGER, OF GIRARD, PENNSYLVANIA.

BALL-BEARING.

No. 903,337.

Specification of Letters Patent.

Patented Nov. 10, 1908

Application filed September 14, 1906. Serial No. 334,600.

To all whom it may concern:

Be it known that I, JOHN F. SPRINGER, a citizen of the United States, and a resident of Girard, in the county of Erie, State of Pennsylvania, have invented new and useful Improvements in Ball-Bearings, of which the following is a specification.

My invention relates to the class of ball bearings which have a plurality of rows of balls, and especially to a subordinate division of this class in which it is sought to effect automatic equalization of pressure as between the various rows of balls, during the operation of the bearing. With the especial objects, thus, of supporting heavy loads, and automatically and continuously distributing the load equally among the rows, my invention consists of features of construction and arrangement producing a new and improved bearing which will be fully described and its novel features claimed.

In the accompanying drawings, Figure 1 is an axial section of an embodiment of my invention. Fig. 2 is also an axial section of 25 an embodiment, but with reversal of parts as compared with Fig. 1. Fig. 3 is a transverse section of the embodiment shown in Fig. 1, at the line 3, 3. Figs. 4, 5, 6, 7, 8, 9, 10, 11, are axial sections of fragments, showing various 30 styles of ball races applicable to the construction shown in Fig. 1, and with reversal of parts, to that shown in Fig. 2. Figs. 12 and 13 are axial sections showing similar and alternative constructions to that shown in Fig. 1. Figs. 14 and 15 show constructions 35 alternative to those shown in Figs. 1 and 2, formed by the omission of certain parts. Fig. 16 is a perspective view of the device used especially to retain in position the separator balls in Fig. 1.

Throughout the drawings, the same letters are used when referring to parts performing similar functions. The word "chamfered" is used to describe broadly a sloping edge, 45 which edge (in section) may be a straight line, the convex side of a curve, or the concave side of a curve. "Carrier" is used broadly as including both shaft and housing, or any two parts performing similar functions. "Race" is sometimes used in sense of groove, and sometimes as denoting the aggregate of all bearing surfaces confining a row of balls.

In Fig. 1, A, is a shaft, B, is a housing. C, 50 is a flange integral with the housing B. Carried by B, and abutting C, is the bearing

ring D, having a chamfered edge d, providing thus a bearing surface. In this particular case the bearing surface d, is concavely chamfered. F, at the other end of the bearing 60 and carried by B, is a ring similar to D, but whose concavely chamfered edge f, is opposed to that of D,. E, are rings carried by B, and each having two concavely chamfered edges e,. Carried by the shaft A, are 65 the rings I, each having two grooves or races, each groove of V-shape and providing two bearing surfaces, i,. In these grooves are rows of balls J, each row of balls having a third and last bearing surface, d, e, or f, 70 in addition to the two bearing surfaces provided by the groove in which it is. G, is an abutting ring for F,; and H, is a locking ring; both G, and H, being in screw-threaded engagement with B,. The three bearing surfaces contacting with a row of balls are mutually so inclined as to confine the balls and at the same time mutually so inclined that radial pressure on the bearing tends to the longitudinal separation of the two rings having the surfaces; that is, of the ring having the groove and of the ring having the chamfered edge. The rings E, and I, are free to slide longitudinally relatively to their respective carriers. If now radial pressure falls 85 unevenly on the bearing, this pressure will tend to be automatically equalized among the several rows by means of the rings free to slide.

The bearing rings J, may be separated by 90 the separator balls K, (Fig. 3), which are preferably of such size and in such position, relatively to the bearing balls, that in the case of any one of the balls K, a straight line joining the centers of the two contiguous 95 balls J, will pass through its center, as shown in Fig. 3. At L, in Fig. 1 is shown in longitudinal section the device used to retain K, in position. L, in Fig. 3 shows a transverse section of the same device, more fully described later. The bearing as thus described will not resist a thrust pressure. By securing from longitudinal sliding, (as by set screws), one or more of the rings E, I, a thrust may be resisted, but at the expense of impairment of equalization of pressure. In order to reduce friction to a very low point, in practice, the inclinations of the bearing surfaces at the points of contact to the axis of rotation of a ball should be but 105 slight. Any or all of the rings D, E, F, I, may be secured from rotation relatively to

their respective carriers by the feather and groove arrangement shown at m_3 and n_3 in Fig. 3. Adjustment of the bearing is secured by means of the ring G_1 which is locked in place by H_1 .

Rings performing the functions of D_1 , E_1 , F_1 , may be mounted on the shaft as shown in Fig. 2. The rings there shown as corresponding to I_1 are arranged in the housing. 10 C_1 is a collar integral with the shaft; and, G_2 and H_2 are adjusting and locking nuts, respectively, G_1 serving as an abutting collar.

Various other forms of ball races providing three-point contact may be used. Such 15 forms are shown in Figs. 4, 5, 6, 7, 8, 9, 10, 11, in all of which, as shown, as well as that shown in Fig. 1, the form of a race is such that a straight line joining the two points of contact of the groove with a ball is parallel 20 with the axis of the shaft. This is usually preferable. But it is not necessary. All that is required is that form be such that radial pressure on the bearing will produce a tendency to longitudinal separation of the 25 two rings forming a ball race. Reversal of the parts of forms shown in Figs. 4, 5, 6, 7, 8, 9, 10, 11, and also of the additional forms just referred to, will produce forms adaptable to the construction shown in Fig. 2. 30 The straight chamfered edge produces equalization most perfectly for the three forms of grooves illustrated, and for their reversals.

In Fig. 12 is shown an alternative construction. C_{12} is a collar integral with the 35 shaft, and against which I_{12} abuts. G_{12} is an adjusting nut against which the ring I''_{12} abuts. H_{12} is a locking nut. The rings I'_{12} and I''_{12} have each but one groove. E_{12} and I_{12} are free longitudinally. By reversing 40 parts a new alternative construction will arise.

In Fig. 13 is another alternative construction. This is representative of the occurrence of an odd plurality of rows of balls. 45 I'_{13} and F_{13} have abutting means, one of which is adjustable, as shown in the figure. E_{13} and I_{13} are free longitudinally. Reversal of parts gives rise to another construction. Both constructions are capable 50 of resisting thrusts.

In Fig. 14 is a construction formed from Fig. 1 by omission of rings E_1 and of all but one of rings I_1 .

In Fig. 15 is shown another construction 55 formed by reversing the parts of Fig. 14.

In Fig. 16 is shown the retaining device, shown in longitudinal section at L_1 (Fig. 1), and in transverse section at L_1 (Fig. 3). This consists of a shell, X , annularly convex 60 at R and cylindrical at O . It is split at S so as to permit of being sprung into position; it has suitable perforations P through which the bearing balls protrude to permit them to bear against the chamfered edges of bearing rings, as shown in Fig. 1. Between the per-

forations are the portions Q which serve to retain the separator balls in position, as shown in Fig. 3. If the perforations are made of suitable size and are suitably placed, the retaining shell will act as ball-retainer 70 for the bearing balls as well as for the separator balls. The dimensions of the shell should be such as to permit it to clear the bearing rings and hold the separator balls in position. The two shells corresponding 75 to a ring I_1 may be made integral with each other. The shell, X , may be given a second cylindrical flange, similar to and axially opposite, the flange O . The bearing shown in Fig. 1 is not shown as equipped throughout 80 with the shells X . This would, of course, ordinarily be done. The method of springing these shells in position on the rings I is as follows, if it is desired that shells act as retainers for the bearing balls as well as for the 85 separator balls. The balls, both separator and bearing balls, are assembled in position in the shell. A ring I is then pressed into position—the split, S , permitting the circlet of balls to yield. 90

If it is not desired that shells act as retainers for the bearing balls, the perforations, P , may be made sufficiently large to permit the passage through them of the bearing balls. There is then no difficulty 95 in assembling. It may also be remarked that it may often seem advisable to make the edges of the perforations, P , blunt, so as to hinder any tendency of the bearing balls to grip the shell, when the bearing 100 is in operation.

Having described my invention, what I claim as new is:

1. In a ball bearing, the combination of two carriers; a bearing ring carried by one of the said carriers and having two grooved ball races, each of said races providing two bearing surfaces, said bearing ring being free to slide longitudinally; two rows of balls in the said races; and, two bearing rings carried by the other of the said carriers and providing by chamfered and proximate edges third and last bearing surfaces for the said rows of balls, both of these said two bearing rings being free to slide longitudinally. 110

2. In a ball bearing, the combination of two carriers; a bearing ring carried by one of the said carriers and having two grooved ball races, each of said races providing two bearing surfaces, said bearing ring being free to slide longitudinally; two rows of balls in the said races; and, two bearing rings carried by the other of the said carriers and providing by chamfered and proximate edges third and last bearing surfaces for the said rows of balls, one of these said two bearing rings being free to slide longitudinally. 120

3. In a ball bearing, the combination of two carriers; a bearing ring carried by one of the said carriers and having two grooved 125

ball races, each of said races providing two bearing surfaces, said bearing ring being free to slide longitudinally; two rows of balls in the said races; and, two bearing rings carried

5 by the other of the said carriers and providing by chamfered and proximate edges third and last bearing surfaces for the said rows of balls.

4. In a ball bearing, the combination of
10 two carriers; a bearing ring carried by one of
the said carriers and having two grooved ball
races, each of said races providing two bear-
ing surfaces, said bearing ring being free to
slide longitudinally; two rows of balls in the
15 said races; and, two bearing rings carried by
the other of the said carriers and providing
by chamfered and proximate edges third and
last bearing surfaces for the said rows of
balls, one of these said two bearing rings be-
20 ing free to slide longitudinally, the other be-
ing prevented by suitable means from longi-
tudinal shifting in one direction.

5. In a ball bearing, the combination of two carriers; a bearing ring carried by one of the said carriers and having two grooved ball races, each of said races providing two bearing surfaces, said bearing ring being free to slide longitudinally; two rows of balls in the said races; and, two bearing rings carried by the other of the said carriers and providing by chamfered and proximate edges third and last bearing surfaces for the said rows of balls, one of these said two bearing rings being prevented by suitable means from longitudinal shifting in one direction.

6. In a ball bearing, the combination of two carriers; two bearing rings carried by one of the said carriers and each having a grooved ball race, each of these races providing two bearing surfaces, both of said bearing rings being free to slide longitudinally; two rows of balls in the said races; and, a bearing ring carried by the other of said carriers and providing by two chamfered edges 40 third and last bearing surfaces for the said rows of balls, this said bearing ring being free to slide longitudinally.

7. In a ball bearing, the combination of two carriers; two bearing rings carried by one of the said carriers and each having a grooved ball race, each of these races providing two bearing surfaces, one of said bearing rings being free to slide longitudinally; two rows of balls in the said races; and, a bearing ring carried by the other of said carriers and providing by two chamfered edges third and last bearing surfaces for the said rows of balls, this said bearing ring being free to slide longitudinally.

60 8. In a ball bearing, the combination of two carriers; two bearing rings carried by one of the said carriers and each having a grooved ball race, each of these races providing two bearing surfaces, both of said bearing rings
65 being free to slide longitudinally; two rows

of balls in the said races; and, a bearing ring carried by the other of said carriers and providing by two chamfered edges third and last bearing surfaces for the said rows of balls.

9. In a ball bearing, the combination of two carriers; two bearing rings carried by one of the said carriers and each having a grooved ball race, each of these races providing two bearing surfaces, one of said bearing rings being free to slide longitudinally; two rows of balls in the said races; and, a bearing ring carried by the other of said carriers and providing by two chamfered edges third and last bearing surfaces for the said rows of balls. 80

10. A ball bearing: comprising two carriers; bearing rings carried by one of the said carriers and each having two grooved ball races, said races each providing two bearing surfaces, said bearing rings being free to slide longitudinally; rows of balls in the said races; and, bearing rings, carried by the other of the said carriers and forming by chamfered edges third and last bearing surfaces for the said rows of balls, the external ones of these rings being prevented by suitable means from longitudinal separation, the remainder being free to slide longitudinally. 85 90

11. A ball bearing: comprising two carriers; bearing rings carried by one of the said carriers and each having two grooved ball races, said races each providing two bearing surfaces, said bearing rings being free to slide longitudinally; rows of balls in the said races; and, bearing rings, carried by the other of the said carriers and forming by chamfered edges third and last bearing surfaces for the said rows of balls, the external ones of these rings being prevented by suitable means from longitudinal separation, one of the remainder being free to slide longitudinally. 95 100 105

12. A ball bearing comprising two carriers; bearing rings carried by one of the said carriers and each having two grooved ball races, said races each providing two bearing surfaces, said bearing rings being free to slide longitudinally; rows of balls in the said races; and, bearing rings, carried by the other of the said carriers and forming by chamfered edges third and last bearing surfaces for the said rows of balls, the external ones of these rings being prevented by suitable means from longitudinal separation. 110 115

13. A ball bearing: comprising two carriers; bearing rings carried by one of the said carriers and each having two grooved ball races, said races each providing two bearing surfaces, one of said bearing rings being free to slide longitudinally; rows of balls in the said races; and, bearing rings, carried by the other of the said carriers and forming by chamfered edges third and last bearing surfaces for the said rows of balls, the external ones of these rings being prevented 130

by suitable means from longitudinal separation, the remainder being free to slide longitudinally.

14. A ball bearing: comprising two carriers; bearing rings carried by one of the said carriers and each having two grooved ball races, said races each providing two bearing surfaces, one of said bearing rings being free to slide longitudinally; rows of balls in the 10 said races; and, bearing rings, carried by the other of the said carriers and forming by chamfered edges third and last bearing surfaces for the said rows of balls, the external ones of these rings being prevented by suitable means from longitudinal separation, one of the remainder being free to slide longitudinally.

15. A ball bearing: comprising two carriers; bearing rings carried by one of the said 20 carriers and each having two grooved ball races, said races each providing two bearing surfaces, one of said bearing rings being free to slide longitudinally; rows of balls in the said races, and, bearing rings, carried by 25 the other of the said carriers and forming by chamfered edges third and last bearing surfaces for the said rows of balls, the ex-

ternal ones of these rings being prevented by suitable means from longitudinal separation.

16. A ball bearing: comprising two carriers, A₁ and B₁; the bearing rings I₁ carried by the carrier A₁ and each having two grooved ball races W, of V-shape, said races each providing two bearing surfaces i₁, said bearing rings being free to slide longitudinally; rows of balls, J₁, in the said races; and, bearing rings, D₁, E₁, F₁, carried by the other, B₁, of said carriers, and forming by concavely chamfered edges, d₁, e₁, f₁, third and last bearing surfaces for the said rows of 40 balls, the external ones, D₁, F₁, of these said rings being prevented by suitable means, C₁, G₁, H₁, from longitudinal separation, the remainder, E₁, being free to slide longitudinally.

In testimony whereof I have hereunto signed my name in the presence of two attesting witnesses, at Girard, in the county of Erie, in the State of Pennsylvania, this 18th day of August, 1906.

JOHN F. SPRINGER.
